UNITED STATES PATENT OFFICE

2,605,427

DIFFUSION-PREVENTING DEVICE FOR
X-RAYS

Roger André Delhumeau, Saint-Mande, France

Application November 18, 1949, Serial No. 128,057
In France November 25, 1948

4 Claims. (Cl. 250—63)

1

It is known that X-rays upon emerging from a body traversed by them undergo irregular deviations which result in diffusion detrimental to the clearness of the observed or radiographed images. To prevent such diffusion it has been suggested to interpose between the body and the screen or plate a diffusion-preventing grid adapted to absorb the deviated rays.

In the early construction of such grids it was first attempted to make use of the absorptive capacity of lead for X-rays. Accordingly the grids were constructed in the form of laminated sheets of a substance having a low absorption rate for X-rays interspersed with fine laminations or layers of lead.

The earlier grids of such construction comprised rather heavy intercalated absorptive laminations, and the pattern formed by the layers or laminations of lead interfered with the image. To eliminate this, devices were used for imparting to the grid a translatory movement in a direction parallel to the plane of the laminations. The production of such movement requires the provision of a rather complicated and cumbersome mechanism which substantially increases the cost of the X-ray outfit. Moreover, it requires that the grid occupy a certain definite position on the table so that the grid can only be used in connection with definite operating procedures.

Accordingly, it has been suggested to construct handier and less expensive grids adapted for use in any selected position. In such construction the grid was provided stationary, it was attempted to bring the absorptive laminations closer together and a thinner grid was used, in which the intercalated laminations were made of resin, cardboard, aluminium, and similar substances. Such grids provide a fine pattern, which is not very troublesome both for X-ray observation and X-ray photography.

Certain types of such grids are focalized, that is to say their laminations throughout the width of the plate have an inclination parallel to that of the central rays to make allowance for the fact that the X-rays are emitted in the form of a conical beam.

Whether or not a focalized grid is used, the construction of the above-described laminated grids of prior art is a delicate process because of the very small thickness or depth (in the order of about $\frac{1}{60}$ mm.) which the laminations or layers of lead have to have, and also the comparatively low thickness of the intermediate permeable layers interspersed therewith, made of aluminium,

cardboard or wood for example. Still further constructional difficulty is encountered when it becomes necessary, in order to provide focalization, to form said permeable intermediate layers

5 with a nonuniform thickness in order to allow for the correct inclination of the various laminations of lead across the grid. Indeed, in some forms of construction in the case of grids with intercalated laminations made of aluminium, 10 focalization cannot be achieved. Focalized grids in which the intermediate laminations are made of materials other than aluminium have the grave shortcoming of being weaker and are apt to crack or split easily whereupon they are liable to overlap in parts and become immediately unserviceable.

This invention has for its object to provide a diffusion-preventing grid for X-ray practice which, as compared with known grids, offers the 15 advantages of being much more simpler to fabricate, allowing very accurate focalization and being much stronger than grids composed of laminated strips.

The grid of the invention is characterized in 20 that it comprises a plate made of a substance permeable to X-rays, formed with narrow closely-spaced grooves extending to only part of its depth, said grooves being filled with a substance impermeable to X-rays.

25 In simple laminated grids forming a lineate pattern, the diffusion-preventing function is performed only in a direction perpendicular to the direction of the lamellae; in a direction parallel with the laminations on the other hand, diffusion is not prevented, whereby such grids only imperfectly fulfil the diffusion-preventing function which is assigned to them.

To avoid this drawback, it has been suggested to superimpose two laminated grids in crossed 30 relationship over each other, but this has other and important drawbacks, in that a dotted pattern becomes superimposed over the lineate patterns at the intersections of the lead laminations, since at such points the absorptive thickness is 35 twice as great than elsewhere. Moreover, and this is the gravest defect, the total depth of the grid is doubled, since two equal depths of intermediate laminations are superimposed, so that substantially longer times of exposure have to be used unless one is willing to accept a substantially reduced degree of screen illumination, which may be very objectionable.

Another object of the invention, accordingly, is to provide a cross-patterned grid comprising a 40 plate of a substance permeable to X-rays formed,

in two preferably perpendicular directions, with narrow closely-spaced grooves filled with a substance impermeable to X-rays. With this arrangement the intersections do not result in an increase in thickness and the depth of the grid remains the same as in the case of a grid having a simple lineate pattern thereon.

In a movable grid, the lines are preferably inclined diagonally with respect to the length dimension of the plate, whereby it is possible to make the pattern lines fade out merely by imparting movement to the grid in a direction parallel to its length.

The accompanying drawings illustrate by way of example, in isometric perspective view, preferred embodiments of grids according to the invention.

Fig. 1 is a fragmentary perspective of a lineate grid according to the invention.

Fig. 2 is a fragmentary perspective of a criss-cross grid according to the invention.

Fig. 3 is a fragmentary sectional view taken on the line III—III of Fig. 1 when the grooves have been filled with a material nonpermeable to X-rays.

Fig. 4 is a similar view of a modification.

Fig. 5 is a diagrammatic view showing the focalization of the grooves of a grid according to Fig. 1.

As shown in Fig. 1, the grid is simply formed by a plate 1 formed at closely spaced intervals, which in the case of fixed grids may be of about 0.4 mm., with channels or grooves 2 about 1.5 mm. in depth and about 0.1 mm. in width, and these grooves are filled with an X-ray absorbent substance 3 (Fig. 3). The pattern effect of such a grid when maintained stationary is quite acceptable. In the case of a grid to be used with a Potter (movable grid) a larger spacing between the grooves may suffice, said grooves being provided, in a manner known per se, with a greater depth.

A grid formed as just described is strong, since it is an integral structure rather than being a laminated assembly. Moreover, it is possible to achieve focalization by progressively inclining the grooves, from the central one to the outermost grooves. Such a focalization is clearly shown in Fig. 5 where 4 designates an X-ray lamp located above a grid according to Fig. 1. This grid is diagrammatically shown in section and it may be seen that the central groove 2m is located in a vertical plane passing through the center of lamp 4 while on either side the grooves 2n are inclined, with the angle of inclination increasing progressively with the distance from the center of the plate so that the projected planes of said grooves converge at the focal point at which the center of the lamp 4 is situated.

Obviously, any suitable materials may be used in such construction, the permeable substance forming the plate being for instance a suitable resin while the X-ray absorbing substance filling the grooves comprises lead or equivalent materials.

The grooved plates of the invention may be produced by a variety of means, as by printing, engraving, cutting, constriction of wider grooves, and the like, and the desired focalization may be secured by suitable adjustment of the tools used in forming the individual grooves, or by bodily distortion of the plate as a whole. One way of producing a focalized grid according to the invention is to cut the grooves therein with a milling machine the cutter of which is progressively

tilted to produce the desired focalization effect.

To fill the grooves with the X-ray absorbent substance, thin sheets of lead foil may be inserted, or the grid may be filled in with the absorbent substance in powder form, or even with a liquid absorbent substance, in which case the grid is surrounded with a frame. One example of such a liquid absorbent substance is mercury, possibly in amalgam form, for instance a silver amalgam which will harden with time. When a liquid is used, the filling step may be carried out in vacuo, by placing an auxiliary plate over the grooved face and sucking in the liquid through the ends of the ducts thus formed.

Figure 2 illustrates a grid according to the invention provided with a criss-cross grooved pattern, wherein, as shown, said grooves 2a and 2b extend perpendicularly to each other, diagonally with respect to the sides 5 and 6 of the grid, whereby, on imparting a displacement to the grid in a direction parallel to the length of the plate, it will be possible to cause a displacement of both sets of lines therein effective to erase the pattern in the image. Obviously, the angles of both sets of parallel lines could differ and the directions thereof could differ. Thus, there would be no objection to forming them parallel with the sides of the plate in the case of a stationary grid.

Moreover, by forming the grooves at sufficiently close intervals, the resulting criss-cross pattern on the image may be made to be in the same order of magnitude as the grain of the plate or paper used, so that its presence will be unimportant. It should be understood that with a focalized criss-cross grid according to the invention the image pattern appears in the form of a fine regular chequer-work, in which the points of intersection do not stand out as they do in the case of a superimposed pair of grids.

According to the modification shown in Fig. 4, the grooved face of the plate 1 may be covered with another, plate 7 having a thickness similar to the solid bottom, said other plate being secured in place by any suitable means such as by a solvent for the nonabsorbent substance. This has the advantage, in addition of protecting the absorbent substance of balancing any strains and stresses which might be developed in the formation of the grooves.

What I claim is:

1. A diffusion-preventing grid for X-ray practice comprising a plane plate of uniform thickness of a substance permeable to X-rays, said plate having formed in one face thereof a series of parallel, uniformly spaced fine grooves of uniform depth which is substantially less than the thickness of said plate, the spacing of said grooves being less than 0.4 mm., the width of the grooves being substantially less than said spacing and the depth of the grooves being greater than the spacing of said grooves and less than 1.5 mm., the side walls of each groove being parallel with one another and at least one groove in the central portion of the plate being substantially perpendicular to the face of the plate while grooves on either side of the central portion are inclined to the face of the plate, with the angle of inclination increasing progressively with the distance from the center of the plate so that the projected planes of said grooves converge at a focal point disposed at a distance from one face of the plate, and a substance impermeable to and absorptive of X-rays filling said grooves.
2. A diffusion-preventing grid for X-ray practice according to claim 1, for use as a fixed grid

in which said grooves form two criss-cross sets of grooves.

3. A diffusion-preventing grid for X-ray practice according to claim 1, for use as a moving grid in which said grooves form two criss-cross sets of parallel grooves symmetrically inclined to the intended direction of reciprocation of the grid.

4. A diffusion-preventing grid for X-ray practice according to claim 1, in which a plate of a substance permeable to X-rays covers the grooves of the grooved plate.
